PULVERIZING MILL

Ervin G. Bailey, Easton, Pa., and Perry R. Cassidy,
Short Hills, and Ralph M. Hardgrove, West-
field, N. J., assignors, by mesne assignments, to
The Babcock & Wilcox Company, Newark,
N. J., a corporation of New Jersey

Application November 16, 1931, Serial No. 575,453

11 Claims. (Cl. 83—45)

The invention relates to pulverizing mills, more particularly such mills wherein grinding balls are used. The invention is especially useful in connection with such mills wherein there is no air separation resulting from a continuous flow of air through the mill.

One object of the invention is the provision of a pulverizing mill wherein the material to be pulverized is given a greater number of successive pulverizations than has heretofore been possible. Another object is the construction of such a mill wherein the displacement of one or more grinding balls in the upper part of the mill will not affect other grinding balls in the same part of the mill, or the pulverizing operation carried out by grinding balls at a different level. A further object is the provision of a pulverizing mill having greater capacity per unit of floor space and per unit of head room than has heretofore been possible. Other objects will appear upon consideration of the following specification.

The invention is shown by way of illustration in the accompanying drawings, wherein—

Figure 1 is a plan view of a mill constructed in accordance with the invention.

Fig. 2 is a vertical section on the line II—II of Fig. 1.

Fig. 3 is a horizontal section on the line III—III of Fig. 2.

Fig. 4 is a horizontal section on the line IV—IV of Fig. 2, and

Fig. 5 is a diagrammatic lay-out of a pulverizing plant in which the invention is employed.

Fig. 6 is a detail of Fig. 2.

In the drawings there is shown a pulverizing mill 10 comprising a casing 11 and grinding rings cooperating with grinding balls therein. One of the grinding rings is a rotatable grinding ring 12 having two concentric ball races therein, these races comprising an inner ball race 13 and an outer ball race 14. Separate sets of grinding balls 15 and 16 respectively operate in the ball races 13 and 14. A separate grinding ring is disposed opposite each set of balls, a grinding ring 17 cooperating with the inner row of balls 15 and a grinding ring 18 cooperating with the outer set of balls 16.

The separate grinding rings 17 and 18 each cooperating with the balls 15 and 16 are stationary and do not rotate, being held against rotation in any convenient manner. As here illustrated, the grinding ring 18 is held against rotation by contact between a lug 18a thereon and a lug 11a on the casing 11; and the grinding ring 17 is held against rotation by contact between

lugs 17a thereon, and lugs 18b on the grinding ring 18. However, the grinding rings may be moved slightly in a vertical direction, each ring being held down upon the grinding balls with which it coacts by resilient compression means. The resilient compression means are here shown as a set of compression springs 19 acting upon the inner grinding ring 17 and a set of compression springs 20 acting upon the outer grinding ring 18. Provision is made for independently adjusting the compression of each of the springs 19 and 20, such adjusting means is here indicated by the bolts 19' and 20' respectively. By providing separate sets of springs for each of two independent grinding rings, it is possible for a piece of hard material to pass beneath one or more balls in one row without disturbing the operation of the other row of grinding balls.

Beneath the rotatable grinding ring 12 there is provided another row or ring of grinding balls 21, which are carried in a lower grinding ring 22 disposed in stationary relationship to the mill. Thus pressure is transmitted from the springs 19 and 20 to the upper grinding rings 17 and 18, thence to the upper grinding balls 15 and 16, and from them to the intermediate rotatable grinding ring 12, whence it is carried to a lower row of grinding balls 21 and to a lower grinding ring 22. By means of the arrangement just described provision is made for varying the grinding pressure throughout the mill in accordance with the hardness of the material to be pulverized.

The intermediate rotatable grinding ring 12 is rotated by a vertical shaft 23, carried by a thrust bearing 23'. The vertical shaft 23 is keyed to a frame 37 which rotates therewith, and a lug 37a on the frame 37 coacts with a lug 12a on the intermediate grinding ring 12 as rotated. By means of this arrangement it is possible for the intermediate grinding ring to "float" vertically, theoretically transmitting no pressure to the vertical shaft 23. As a practical matter there will be friction between the faces of the lugs 12a and 37a, which will result in some vertical thrust being transmitted to the shaft 23. A spur gear 24, provided upon the vertical shaft 23, meshes with a spur gear 25 on a vertical stub shaft 26, on which there is also a bevel gear 27. The bevel gear 27 on the stub shaft 26 meshes with another bevel gear 28 on a drive shaft 29. The apparatus is driven from the drive shaft 29 by interposing the stub shaft 26 between the vertical shaft 23 and the drive shaft 29, and by operating the vertical shaft 23 from the stub shaft 26 by means of the spur gears 24 and 25 provision is

made for preventing the transmission of vertical thrust from the vertical shaft 23 to the gear connections between the vertical shaft and the drive shaft 29. More perfect alignment and more satisfactory operation of the mill is thereby assured.

The material to be pulverized is contained in a hopper 30, preferably above the mill. From this hopper the material descends by means of any convenient apparatus, here illustrated as a chute 31, and a weighing feeder 31' leading to a chute to the top of the mill casing 11, where it enters the mill. Upon entering the mill the material to be ground falls upon the top of an upwardly inclined conical member 32 which is carried by 15 the rotatable intermediate grinding ring 12, and thence passes by centrifugal force and gravity beneath the inner row of upper grinding balls 15. An upwardly extending fin 33 on the conical member 32 assists in moving the material to be 20 pulverized beneath the inner row of upper grinding balls 15. The first stage of pulverization is carried on between the inner row of upper grinding balls 15 and the inner grinding race 13 on the intermediate grinding ring 12, the material passing 25 outwardly by means of centrifugal force to a position between the outer row of upper grinding balls 16 and the outer grinding race 14. In this latter position, the material undergoes a second stage of pulverization and passes outwardly of the mill, 30 the fine material descending through an annular opening 34 and the outer edge of the intermediate grinding ring. The annular opening 34 is adjustable, an annular ring 35 being provided which may be moved nearer to or further from the intermediate grinding ring by means of a bolt 35a. Material which is too coarse to pass through the 35 annular opening 34 piles up outside of the outer row of grinding balls 16 and eventually slides back into the grinding race 14 by gravity.

40 Material passing through the annular opening 34 falls to a position outside of the lower row of grinding balls 21, whence it passes by gravity between this lower row of grinding balls and the lower grinding ring 22. Here the material under- 45 goes the third stage of its pulverization, working inwardly and falling through an annular opening 36 between the lower grinding ring 22 and a member 37 rotatably carried by the vertical shaft 23.

50 From the foregoing it will be apparent that the materials are moved in a generally radial direction of the mill during the successive stages of pulverization, beneath the two upper rows of grinding balls, and are there subjected to successive stages of pulverization at substantially the same elevation. The materials are then dropped to a lower plane, that is to say, to the level of the lower row of grinding balls 21, and are there passed in an opposite radial direction while being 55 subjected to further pulverization.

Falling through the annular opening 36, the material, which has now been pulverized, enters a chamber 38 which is swept by a plurality of sweeps 39 carried by the member 31. The plurality of sweeps 39 impart a rotary action to the pulverized material which is carried by centrifugal force to a chute 40 which carries it out of the mill.

As illustrated in Fig. 5, the chute 40 may pass 70 the pulverized material to a bucket conveyor 41, which in turn elevates the material to a second chute 42, which delivers the material to a mechanical separator 43 having a hopper bottom 44a. The fine material is separated from the coarse 75 and conveyed to the hopper bottom 44a whence

it may be withdrawn through a chute 45 to a suitable conveying apparatus 46, here illustrated as a Fuller-Kinyon pump. The coarse material is deposited in an inner hopper 44 and returned to the pulverizer through a return pipe 47 for further pulverization.

By subjecting the material to a greater number of pulverizing operations than has been possible in previously constructed apparatus, and by separating the fine material so pulverized from the coarse externally of the mill, more rapid travel of the material through the mill is effected and a greater capacity per unit of floor space and head room is realized.

The embodiment of the invention illustrated in the drawings and specifically described in this specification, is presented merely by way of example, and is not to be considered as limiting the invention. With this understanding therefore, we claim—

1. A pulverizer comprising a casing enclosing an upper circular row of rolling grinding elements constituting an upper pulverizing stage having an outward flow of material therethrough, an intermediate grinding ring supporting said upper row of elements, an upper grinding ring supported on said upper row of elements, means for exerting a grinding pressure on said upper row of elements, a material feed opening in the upper portion of said casing arranged to deliver material to the inner side of said upper row of elements, a lower grinding ring arranged below said upper row of elements, a lower row of rolling grinding elements positioned between said intermediate and lower grinding rings and constituting a lower pulverizing stage receiving material by gravity from said upper pulverizing stage and having inward flow of material therethrough, means at the outer side of and out of contact with said upper row of elements and arranged to cooperate with said intermediate grinding ring in partly damming the outward flow of material from said upper pulverizing stage, and rotary means receiving and ejecting from said casing the material leaving the inner side of said lower row of elements.

2. A pulverizer comprising a casing enclosing an upper circular row of rolling grinding elements constituting an upper pulverizing stage having an outward flow of material therethrough, an intermediate rotary grinding ring supporting said upper row of elements, an upper grinding ring supported on said upper row of elements, means for exerting a grinding pressure on said upper row of elements, a material feed opening in the upper portion of said casing, means on said intermediate ring arranged to receive material from said feed opening and to direct the material to the inner side of said upper row of elements, a lower grinding ring arranged below said upper row of elements, a lower row of rolling grinding elements positioned between said intermediate and lower grinding rings and constituting a lower pulverizing stage receiving material by gravity from said upper pulverizing stage and having an inward flow of material therethrough, adjustable means forming a ledge gap of variable flow area between said rotary intermediate ring and said casing in the path of material flow between said upper and lower pulverizing stages, and rotary means receiving and ejecting from said casing the material leaving the inner side of said lower row of elements.

3. A pulverizer comprising a casing enclosing

upper inner and outer concentric rows of rolling grinding elements constituting first and second pulverizing stages having an outward flow of material therethrough, a rotary intermediate 5 grinding ring supporting said inner and outer rows of elements, a plurality of concentric stationary upper grinding rings respectively supported on said inner and outer rows of elements, means for exerting independently adjustable 10 grinding pressures on said inner and outer rows of elements, a material feed opening in the upper portion of said casing arranged to deliver material to the inner side of said upper inner row of elements, a lower stationary grinding ring, a 15 lower row of rolling grinding elements positioned between said intermediate and lower grinding rings and constituting a third pulverizing stage receiving material by gravity from said second pulverizing stage and having an inward flow of 20 material therethrough, means at the outer side of and out of contact with said upper outer row of elements and arranged to cooperate with said intermediate grinding ring in partly damming the outward flow of material from said second 25 pulverizing stage, and rotary means receiving and ejecting from said casing the material leaving the inner side of said lower row of elements.

4. A pulverizer comprising a casing enclosing upper inner and outer concentric rows of rolling 30 grinding elements constituting first and second pulverizing stages having an outward flow of material therethrough, a rotary intermediate grinding ring having inner and outer grinding tracks supporting said inner and outer rows 35 of elements respectively, said outer track being arranged at a higher elevation than said inner track to retard the flow of material between said first and second pulverizing stages, a plurality of concentric stationary upper grinding 40 rings respectively supported on said inner and outer rows of elements, means for exerting independently adjustable grinding pressures on said inner and outer rows of elements, a material feed opening in the upper portion of said casing arranged to deliver material to the inner side of said upper inner row of elements, a lower stationary grinding ring, a lower row of rolling grinding elements positioned between said 45 intermediate and lower grinding rings and constituting a third pulverizing stage receiving material by gravity from said second pulverizing stage and having an inward flow of material therethrough, means at the outer side of and out 50 of contact with said upper outer row of elements and arranged to cooperate with said intermediate grinding ring in partly damming the outward flow of material from said second pulverizing stage, and rotary means receiving and ejecting 55 from said casing the material leaving the inner side of said lower row of elements.

5. A pulverizer comprising a casing enclosing inner and outer concentric rows of rolling grinding elements, a rotary grinding ring supporting 60 said inner and outer rows of elements, inner and outer concentric non-rotary grinding rings respectively supported on said inner and outer rows of elements, means for exerting independent 65 grinding pressures on said inner and outer rows of elements comprising a circular series of compression springs adjacent the side wall of said casing and arranged to act on said outer grinding ring, and a second series of compression springs 70 arranged to act on said inner grinding 75

ring and arranged in the same circular row as said first named series of compression springs.

6. A pulverizer comprising a casing enclosing inner and outer concentric rows of rolling grinding elements, a rotary grinding ring supporting 5 said inner and outer rows of elements, inner and outer concentric non-rotary grinding rings respectively supported on said inner and outer rows of elements, means for exerting independent grinding pressures on said inner and outer rows 10 of elements comprising a circular series of compression springs adjacent the side wall of said casing and acting solely on said outer grinding ring and extending through the top of said casing, and a second series of compression springs 15 acting solely on said inner grinding ring and extending through the top of said casing and arranged in the same circular row as said first named series of compression springs.

7. A pulverizer comprising a casing enclosing inner and outer concentric rows of rolling grinding elements, a rotary grinding ring supporting 20 said inner and outer rows of elements, inner and outer concentric non-rotary grinding rings respectively supported on said inner and outer rows 25 of elements, means for exerting independent grinding pressures on said inner and outer rows of elements comprising a circular series of compression springs held between said outer grinding ring and the top of said casing adjacent the side wall of said casing, bracket arms extending outwardly from said inner grinding ring, and a second series of compression springs held between 30 said inner grinding ring bracket arms and the top of said casing and arranged in the same circular row as said first named series of compression springs.

8. A pulverizer comprising a casing enclosing inner and outer concentric rows of rolling grinding elements, a rotary grinding ring supporting 35 said inner and outer rows of elements at different elevations, inner and outer concentric non-rotary grinding rings respectively supported on said inner and outer rows of elements, means for exerting independent grinding pressures on said inner and outer rows of elements comprising a circular series of compression springs held between 40 said outer grinding ring and top of said casing adjacent the side wall of said casing, a second series of compression springs held between said inner grinding ring and the top of said casing and arranged in the same circular row as said first named series of compression springs, 45 and externally operable means for separately adjusting the compression of each of said compression springs.

9. A pulverizer comprising a casing enclosing upper inner and outer concentric rows of rolling grinding elements constituting first and second pulverizing stages having an outward flow of material therethrough, a rotary intermediate grinding ring having inner and outer grinding tracks supporting said inner and outer rows of elements respectively, said outer track being arranged at a higher elevation than said inner track to retard the flow of material between said first and second pulverizing stages, a plurality of concentric non-rotary upper grinding rings respectively supported on said inner and outer rows of elements, means for exerting independently 60 adjustable grinding pressures on said inner and outer rows of elements, a material feed opening in the upper portion of said casing arranged to deliver material to the inner side of said upper inner row of elements, a lower non-rotary grind- 65

70

75

- ing ring, a lower row of rolling grinding elements positioned between said intermediate and lower grinding rings and constituting a third pulverizing stage receiving material from said second 5 pulverizing stage and having an inward flow of material therethrough, and rotary means receiving and ejecting from said casing the pulverized material leaving the inner side of said lower row of elements.
- 10 10. A pulverizer comprising a casing enclosing a lower rotary grinding ring, inner and outer concentric rows of rolling grinding elements supported on said lower grinding ring, vertically movable inner and outer concentric non-rotary 15 grinding rings mounted on said inner and outer rows of elements respectively, means extending between said outer grinding ring and said casing for preventing rotation and permitting tilting of said outer grinding ring, and means extending 20 between said inner and outer grinding rings for preventing rotation and permitting tilting of said inner grinding ring.
11. A pulverizer comprising a casing enclosing a lower rotary grinding ring, inner and outer concentric rows of rolling grinding elements supported on said lower grinding ring, vertically movable inner and outer concentric non-rotary 5 grinding rings mounted on said inner and outer rows of elements respectively, means for exerting independent grinding pressures on said inner and outer grinding rings, means extending between said outer grinding ring and said casing for preventing rotation and permitting tilting of 10 said outer grinding ring, and means extending between said inner and outer grinding rings for preventing rotation and permitting tilting of 15 said inner grinding ring.
